UNITED STATES PATENT OFFICE.

JOHN G. MAGIN, OF ROCHESTER, NEW YORK, ASSIGNOR TO HENRY CONOLLY COMPANY,
OF ROCHESTER, NEW YORK, A CORPORATION OF NEW YORK.

LOOSE-LEAF BINDER.

1,083,113.

Specification of Letters Patent.

Patented Dec. 30, 1913.

Application filed October 30, 1912. Serial No. 728,656.

To all whom it may concern:

Be it known that I, JOHN G. MAGIN, of Rochester, in the county of Monroe and State of New York, have invented a new and useful Improvement in Loose-Leaf Binders, which improvement is fully set forth in the following specification and shown in the accompanying drawings.

The present invention relates to loose leaf binders and an object of the same is to improve the hinges of the covers in order to obtain greater durability and cheapness of construction.

Another object of the invention is to provide, in that type of loose leaf binder having a removable transfer member, means for supporting the transfer member in the binder when said transfer member is removed from its normal position.

To these and other ends the invention consists in certain parts and combinations of parts all of which will be hereinafter described, the novel features being pointed out in the appended claims.

In the drawings: Figure 1 is a perspective view of the binder in open position, with the leaves removed and the transfer member removed from its normal position but supported on the binder; Figs. 2 and 3 are plan views of the two hinge connections; Fig. 4 is a sectional view of the loose leaf binder, transverse of the hinge connections; and Figs. 5, 6 and 7 are detail perspective views of portions of one of the hinge connections.

Referring more particularly to the drawings, *a* and *b* indicate two cover members hinged, preferably in a manner to be described, to two intermediate or connecting members *c* and *d* which, in turn, are hinged to a back piece *e*, the intermediate connecting members carrying the binding means for the leaves. The binding means, in this instance, comprises a strip of metal 1 forming a supporting member for one or more posts or impaling projections 2 projecting upwardly therefrom in parallel relation and preferably having an oval cross section, their upper ends being provided with notches 3 forming shoulders for engagement by retaining means carried by the intermediate or connecting member *c* of the cover *a*. In this instance, the intermediate member carrying the retaining means embodies two

strips of material 4 and 5 substantially U- shape in cross section and one housed within the other to provide a casing for a retaining or latch bar 6. The latter may be slidably or otherwise arranged within said casing and moved in one direction by a spring 7 and in the other direction through the means of a finger piece 8 projecting from one end of the retaining casing, said bar having openings therein to fit over the upper ends of the posts or impaling projections 2 and engage in the notches 3 as is common in this art.

The leaves are formed with openings corresponding to the cross sections of the posts 2 in order to fit over said posts. They are also provided with openings for receiving the projections or posts 9 on the transfer member which may comprise a bar 10 provided with openings 11 adapted to fit over the upper ends of the posts 2 and to be held in position thereon by the retaining means before described.

A feature of this invention is the construction of the hinges between the cover members *a* and *b* and the intermediate connecting members *c* and *d*. Both of the cover members are preferably made from two sheets of card board, 12 and 13, having a suitable covering 14 and between these two sheets of card board of each cover is secured one of the hinge members which, preferably, comprises a single piece of metal bent upon itself to provide two leaves 15 and 16 connected by a bead or tubular portion 17, said tubular portion being cut at intervals to provide recesses or notches 18. Through this tubular portion 17 extends a hinge pintle or rod 19 which is exposed at the notched portions 18 for engagement by portions on the intermediate or connecting members *c* and *d*.

On the member *c* are provided two straps of sheet metal, each bent upon itself to provide two abutting portions 20 and 21 and a tubular portion connecting the portions 20 and 21 and surrounding the pintle 19. The portions 20 and 21 of each strap are extended through a notch in the member 4 and an opening 24 in a flange of the member 5, being riveted to the inside of the latter at 32, so that the tubular portion 22 projects from one side of the member 4.

On the intermediate member *d* are pro-

vided two straps each bent intermediate of its ends to provide a tubular portion 24 surrounding the pintle 19 and two arms 25 lying on opposite sides of the bar 1 and riveted at 26 thereto, a filling piece 24 being introduced between the arms 25 to confine the pivot pin 19. The intermediate or connecting members *c* and *d* and the backing piece *e* have common covering 27 which, at 10 28, serves as a hinge between the aforesaid parts, and also covers the exposed portions of the hinge straps. The coverings 14, of covers *a* and *b*, are extended over the tubular portions 17 and in this way the hinges 15 are concealed.

In loose-leaf binders having removable transfer members with impaling projections, it has been found that, when there are but a few loose leaves on the transfer member, 20 the latter is liable to topple over owing to the fact that the bar 10 is not sufficiently wide to provide a suitable base. This has been found to be particularly disadvantageous when the loose-leaf binder is used in connection with book typewriting machines 25 where the leaves are transferred, one at a time, onto the transfer member. To overcome this disadvantage, there has been provided, on the binder, suitable means for supporting the transfer member when the latter is removed from the impaling posts 2, such support being, preferably, so located that the undermost leaf thereon rests almost entirely upon one of the cover members.

To the above end, there are preferably arranged, on the inner face of the cover member *a*, suitable supporting devices for holding the transfer member to the binder. These supporting members are in the form 40 of spring clips each preferably formed from a single piece of metal bent to provide a U-shaped portion 29 lying in close proximity to the hinge of the cover member *a* and opening toward the free end of said cover member, one arm of the clip being free and having a retaining nose 30, and the other arm having an attaching portion 31 secured to the cover member *a*, said attaching portion being offset at 32 and lying parallel with the 45 cover member which is provided with a pocket at 33 so that the attaching portion may be countersunk in the cover *a* and concealed by the covering 14. The supporting members may be secured to the hinge member of the cover *a* by screws 34 and the hinge member may be reinforced at 35 by a block in order to provide an anchor for the screws 34.

A loose-leaf binder constructed in accordance with this invention is provided with 60 hinges which are durable in use and economical to manufacture. The transfer member is adapted to be so supported that the leaves thereon may lie upon one of the 65 cover members while the leaves on the im-

paling posts lie on the other cover member without interfering with the assembling of the leaves on the two members.

What I claim as my invention and desire to secure by Letters Patent is:

1. A member for a hinged connection for a loose leaf binder comprising two parts forming a casing between them, one of said parts being of U shape in cross section and having an opening on one side, and a strap formed of a single piece of material bent upon itself to form a tubular portion and a portion which extends through the opening in the U-shaped member and is secured to the interior thereof.

2. A member for a hinged connection for loose leaf binders comprising a casing formed of two pieces, U-shaped in cross section, and fitting one within the other, one of said pieces being notched at one edge and the other of said pieces having an opening in its side, a strap formed of a single piece of material bent upon itself to provide a tubular portion and a portion which extends through the notched portion and the opening of the two U-shaped members and is secured within one of said members.

3. A hinge connection for loose leaf binders comprising a hinge member formed from a single sheet of material bent upon itself to provide a tubular portion and a portion to be secured to the cover, the tubular portion being notched, and a casing formed of two members U-shaped in cross section and fitting one within the other, one of said members being notched at its edges and the other of said members having an opening in its side, a hinge member formed of a single piece of material bent upon itself to provide a tubular portion and a portion which extends through the notched portion and the opening of the two U-shaped members and is secured to the interior of one of said U-shaped members, the tubular portion of the hinge member fitting 100 in the notched portions of the first named hinge member and connected with the latter to permit a swinging movement.

4. In a loose leaf binder, the combination with a pair of binding strips, one of which has rigid impaling projections permanently carried thereby and the other of which is provided with means for engaging said projections to hold the binding strips together, covers hinged to said binding strips, a transfer member having a projection for co-operation with sheets on the impaling projections, and means for supporting said transfer member with its projection upright, in proximity to the hinge of the cover which is secured to the strip with said engaging means so that leaves may be supported on said cover by said transfer member.

5. In a loose leaf binder, the combination

- with a supporting member having impaling projections extending therefrom, and a cover member hinged to said supporting member, of a retaining member coöperating
- 5 with said impaling projections, a cover member hinged to said retaining member, removable transfer member arranged to coöperate with sheets while the latter are supported on the impaling projections, and
- 10 means arranged on the inner face of the cover that is hinged to the retaining member, said means being arranged to support the removable transfer member.
6. In a loose leaf binder, the combination
- 15 with a back piece, connecting pieces hinged to the back piece, cover members hinged to the connecting pieces, impaling projections extending from one of said connecting pieces, retaining means on the other connecting piece coöperating with the impaling projections, and a removable transfer member embodying a bar and projections extending therefrom and adapted to be passed
- 20 through sheets on the impaling projections, of means on that cover member which is hinged to the connecting piece carrying the retaining means, said means being adapted to coöperate with the bar of the transfer member in order to hold the projections thereon upright when the loose leaf binder is open.

7. In a loose leaf binder, the combination with a back piece, connecting pieces hinged to the back piece, cover members hinged to the connecting pieces, impaling projections extending from one of said connecting pieces, retaining means on the other connecting piece coöperating with the impaling projections, and a removable transfer member embodying a bar and projections extending therefrom and adapted to be passed

through sheets on the impaling projections, of means on that cover member which is hinged to the connecting piece carrying the retaining means, said means being adapted to coöperate with the bar of the transfer member in order to hold the projections thereon upright when the loose leaf binder is open.

8. In a loose leaf binder, the combination with a back piece, connecting pieces hinged to the back piece, cover members hinged to the connecting pieces, impaling projections extending from one of said connecting pieces, retaining means on the other connecting piece coöperating with the impaling projections, and a removable transfer member embodying a bar and projections extending therefrom and adapted to be passed through sheets on the impaling projections, of means on that cover member which is hinged to the connecting piece carrying the retaining means, said means comprising spring clips opening toward the free edge of the cover member and adapted to grip the bar of the transfer member.

9. In a loose leaf binder, the combination with a back piece, connecting pieces hinged to the back piece, covers hinged to the connecting pieces, and binding means comprising impaling means on one of the connecting pieces and retaining means on the other connecting piece, of a removable transfer member held by the binding means, and means arranged on the inner face of one of the covers to support said transfer member.
